COLLAPSIBLE BOAT

James F. Cooper, Akron, Ohio, assignor to Wing-foot Corporation, Akron, Ohio, a corporation of Delaware

Application August 31, 1940, Serial No. 355,067

7 Claims. (Cl. 9—2)

This invention relates to collapsible and portable boats, and it refers particularly to inflatable fabric boats and to novel means for adding greater utility and safety in providing the boat with a pneumatic pad which is fitted to the bottom of the boat to form a floor.

Prior to this invention, portable inflatable boats have been used by sportsmen, campers, explorers, searching parties, and rescue workers in times of disaster caused by floods, etc.

Since the provision has been made for mounting an outboard motor on a boat of this type, as disclosed in my Patent No. 2,150,420, such boats have been more generally accepted on account of the increased utility made possible by such a motor mounting over a boat that could be propelled by oars only.

Although boats of this nature equipped with outboard motors are generally satisfactory up to a certain speed, it has been found that by the application of this invention greater speed, comfort and safety may be obtained.

In its broad aspect, one of the features of the present invention is the application of a pneumatic bottom to an inflatable fabric boat which will substantially aid in the maneuverability of the boat. The pneumatic bottom may be an integral part of the boat or it may be separately formed and capable of being quickly and easily installed or removed from the boat and when removed may be used as a raft or mattress. It also adds substantially to the buoyancy of the boat but an important function of the floor is that it adds to the rigidity of the boat both sideways and lengthwise, and the lengthwise rigidity enables the boat to be driven at a greater speed with less tendency of flexing or buckling which would permit the bow of the boat to rise too far out of the water. In fact the pneumatic floor permits the boat to retain a more even keel.

Another feature of the pneumatic floor is that it serves as a protection when the boat is beached or traveling through shallow water where the bottom could come in contact with sharp pointed objects such as rocks, logs, etc. When an obstruction of this nature contacts the bottom of the boat directly beneath an object of considerable weight which may lie on the floor of the boat, the pneumatic floor will form a cushion between such contacting surface and prevent damage to the bottom by cushioning, whereas serious damage may otherwise result.

Another feature of the invention is the provision of a pneumatic cylindrical tube extending around the outer sides and across the bow of the

boat for the purpose of preventing spray formed by waves, or the disturbance of the boat passing through the water from entering the boat, thus keeping the interior dry. This spray tube also serves the purpose of a bumper or buffer to protect the main body of the boat should it come in contact with an object that would be injurious to the main fabric body.

Another feature of the invention is the provision of a quick release device which may be used in case boats of this type are required to be towed. The boat is so constructed that it may be deflated and rolled up in a very compact bundle and a considerable number of them can be stored aboard a larger boat or ship in a comparatively small space. When a ship is on an exploring or searching expedition, or the like, and it is desired to land a considerable number of men simultaneously the collapsible boats may be inflated and launched into the water and towed through the aid of a tow line as close to the shore as the large ship can safely navigate. The small collapsible boats can then be released by a quick release device, their motors started, and proceed to land, even though the water may be very shallow. The small boats, being very buoyant, are able to navigate water that is from four to six inches deep, depending on the load.

The foregoing and other objects, features and advantages of the invention will be readily appreciated from the following description in conjunction with the accompanying drawings wherein in the invention has been shown by way of example and wherein

- 35 Figure 1 is a top plan view of the improved boat with the improvements shown therein;
  - Fig. 2 is a side elevation thereof;
  - Fig. 3 is a side view of one of the tow-line attachments;
  - 40 Fig. 4 is a plan view of same;
  - Fig. 5 is a sectional view taken on the line 5—5 of Fig. 1 somewhat enlarged;
  - Fig. 6 is a plan view of the pneumatic floor with a part broken away to more clearly show details of construction;
  - 45 Fig. 7 is a fragmentary sectional view taken on the line 7—7 of Fig. 6;
  - Fig. 8 is a fragmentary sectional view taken on the line 8—8 of Fig. 6; and
  - 50 Fig. 9 illustrates one method of constructing the pneumatic floor.
- By referring first to Figs. 1 and 2, it will be seen that the boat 10 there shown is equipped at its stern with a motor mounting 11 to which is secured an outboard motor 12 of any ordinary

or preferred form. The motor mounting is fully described in Patent Number 2,150,420 previously issued to me and will not be described herein. The boat 10 comprises a tubular buoyant frame made up of a number of tube sections 14^a, 14^b, 14^c, 14^d, 14^e, 15^a, 15^b, 15^c, 15^d and 16. These tube sections are formed of air-tight and water-proof, flexible material, such as rubberized fabric, and may be joined together with lapped edges which may be cemented, vulcanized, stitched or otherwise. It is to be noted that the bow sections 14^a and 15^a mutually converge to a point in plan, and that they are inclined upwardly, whereby to provide minimum resistance to propulsion. The stern tube section 16 is of course transversely disposed and is adapted for the attachment of the motor mounting 11. It is also to be understood that the tube sections which make up the boat frame are of substantially circular cross section and sufficiently large to provide adequate buoyancy when inflated. Secured to the lower sides of all of said tube sections and completely filling the space therebetween is a water-proof fabric bottom 17, the detail of which is best shown in Fig. 5. If desired, the edges of this bottom 17 may be lapped by securing patches 18, whereby to strengthen the connection between the parts. Canvas strips 19, 20 and 21 extend crosswise in the boat to provide seats for some of the occupants; the ends of these canvas strips are cemented to the adjacent portions of the tubular frame sections.

It is to be noted that the seat strip 21 is disposed at substantially the widest part of the boat and the strip 20 somewhat to the rearward and, because of the general flexibility of the entire structure, it is desirable to provide means for resisting inward movement of the tube sections 14^c and 15^c when weight is applied to the seat. One way of accomplishing this is by pneumatic struts 22 and 23, as best shown in Fig. 1. These pneumatic struts consist of a tube of air-tight and water-proof fabric, having their ends flared and secured to the adjacent portions of the frame tube sections 14^b, 14^c, 15^b and 15^c. Preferably, these pneumatic tube struts may be separately inflated with air through the valves 24 and 25 of any preferred type. Furthermore, these pneumatic struts are disposed directly below the seat strips 20 and 21 and are spaced above the boat bottom 17, whereby the seat is made more comfortable and the bottom of the boat is entirely clear from stem to stern. Since the pneumatic struts 22 and 23 resist transverse collapse of the boat, it makes possible an increase in boat width and thus increases the boat's carrying capacity.

The boat is equipped with handles 27 by which it may be carried, or oars may be inserted in the openings therein for rowing, if found necessary. A rope 28 is attached to the upper side of the boat, to which persons may cling in case of rescue work or accident, and may also be used as an aid in launching or removing the boat from the water.

Referring now to the pneumatic floor 30, it will be noted that the floor takes a shape to conform with the shape of the boat when viewed in plan and is composed of a plurality of air compartments 31, 32, 33 and 34, each of which is subdivided into a plurality of tubular air chambers 35 for the purpose of retaining a flat floor-like shape when inflated. Referring to Fig. 7, the pneumatic floor is composed of relatively long strips of fabric 36, the longitudinal central portions of which are coated with cement. Then

the strips are cemented together in pairs as indicated by the numeral 37, leaving the edge portions 38 free. The edge portions are then cemented to sheets of canvas 39 and 40. After a series of such strips are thus assembled, a binding strip 41 is cemented all the way around the edges of the assembly for added reinforcement. In order to provide separate air compartments 31, 32, 33 and 34, a solid partition is formed by the meeting surfaces of two of the strips 36 which extend from end to end of the pneumatic floor at these particular points. A reinforcing strip 43 is then applied over the ends of the partition (see Fig. 8). The ends of the tubular members which are separated by the partition are provided with openings 44 in each side adjacent the abutting ends of the partition, to permit air to penetrate into the remaining tubular compartments 35 which are terminated short of the end wall to permit free access of air thereto, as indicated at 46 of Fig. 6.

In fabricating the pneumatic floor it has been found advantageous to form the air chambers by applying the fabric strips 38 to mandrels 52 which are of rectangular cross-section (see Fig. 9). The fabric strips 38 are lightly cemented to the mandrels, then the mandrels with the fabric thereon are placed side by side and pressed firmly together. The top and bottom covers 39 and 40 are cemented to the portions of the strips 38 that overlap the top and bottom of the mandrels 52. The mandrels are then removed and the edges of the pneumatic floor are then finished as stated before.

The spray tube guard 53 is of tubular form having a single continuous air chamber, and is cemented to the outside wall of the tubular frame of the boat 10 and slightly above the transverse center line thereof, through the aid of reinforcing strips of fabric 54. The spray tube 53 extends from the rearward end of the boat 10 along the sides and across the bow and is inflated by the valve 55. By the addition of this spray guard the boat has been made much more comfortable for its occupants by preventing spray from entering the boat.

The towing mechanism is composed of two boat attachment members 56 in the form of pressed steel plates having a raised hollow boss 57. The boss 57 is provided with an oblong opening 58 in the upper edge of which is formed a notch 59. These pressed steel plates are attached to the body of the boat at the forward end and somewhat below the transverse center line thereof by fabric patches of conventional form which are cemented to the fabric boat body. Hooks formed so that they may be readily attached and released from the plates 56 are in the form of a cylindrical metal bar 60, one end of which is bent at right angles to the main body and provided with a flange 61, the upper side of which has a lug 62 extended therefrom. It will be noted that the flange 61 is oblong in form and when the hook is in an upward vertical position and the lug 62 is in alignment with notch 59 of the hollow boss 57, the flange will enter the oblong opening and be locked in said boss when in a horizontal or downward vertical position. The other ends of the hooks are provided with eyes 63 to which cables 64 are attached and are extended for connection to a quick release device 65 of any ordinary or preferred form. A cable 66 is attached to the other end of the quick release device for attachment to a larger boat, whereby the inflatable boat may be towed. The cable 67 has

one of its ends permanently attached to the bow of the boat and the other end attached to a rod 68, and when the occupants of the boat desire to be released, the cable 67 is pulled which forces the rod rearwardly against the compression of a spring 69, this in turn causing the sliding block 70 to recede and disengage the end of a hook 71 from an opening in the end of said sliding block. When this occurs the hook 71 will fall downward and permit the cable 66 to slide off the hook releasing the boat, after which the towing mechanism may be withdrawn into the boat whereupon it can proceed on its own power.

At certain times it may be desirable to land a comparatively large party simultaneously. In such case a large boat could tow a number of inflatable boats as near to shore as safety will permit, whereupon the boats can be released and proceed to shore through water which a larger boat would be unable to navigate.

From the foregoing it will be evident that an improved inflatable boat has been provided and the various improvements described will substantially add to the comfort and utility of such boats generally. A combination of these units is particularly advantageous to sportsmen, searching or rescue parties. Obviously the several features of the invention may be modified in various ways and the right is herein reserved to make such changes as fall within the scope of the appended claims without departing from the spirit of the invention.

Having thus described the invention, what is claimed is:

1. A collapsible inflatable boat of the class described comprising a boat body having flexible fabric sides and bottom, the sides being tubular and inflatable to provide buoyancy, a removable and separately inflatable pneumatic floor fitting snugly within the bottom of the boat and assisting in maintaining the shape of the boat, a tubular pneumatic spray guard secured to the outer sides of the boat body, a safety line attached to the body of said boat above the spray guard, a towing mechanism comprising a quick-release mechanism and means for attachment of said towing mechanism to the opposite sides of the boat body at points below the spray guard, and means for attaching an outboard motor to propel said boat.

2. In a collapsible inflatable boat of the class described, a flexible fabric boat body having inflatable tubular side and end members, a removable pneumatic flexible floor fitted snugly in the bottom of said boat, a pneumatic spray guard attached to the outer sides of the tubular body members of the boat, said pneumatic floor and spray guard contributing reinforcement for helping to maintain the shape of the boat in service, and a towing mechanism associated with the forward portion of the boat, said towing mechanism having plural connections with the boat body so that towing forces are distributed to the fabric with minimum distortion of the boat body.

3. A boat of the class described comprising an inflatable tubular fabric frame constituting complete side and end portions of the boat, a flexible waterproof fabric bottom secured to said frame and stretched between said side and end portions at the lower surfaces thereof, and a separately inflatable removable cellular fabric bottom superimposed on said first mentioned bottom with its edges contacting the tubular fabric frame of the boat to assist in maintaining the shape of the boat in use and to add buoyancy thereto.

4. A boat of the class described comprising a boat body having side and end portions each formed of a single tube of flexible fabric and capable of inflation to provide desired degree of buoyancy, and a flexible pneumatic floor in said boat body, said floor being separately inflatable and adapted to exert outward lateral pressure against the side and end portions of the boat body whereby to resist deformation of the boat in service, and towing connections at opposite points of the outer surfaces of the tubular side portions of the boat body, said towing connections being disposed substantially in the plane of the pneumatic floor.

5. In a pneumatic collapsible boat of the class described, a flexible fabric boat body having inflatable tubular side and end members, and a spray guard extending continuously from the bow to adjacent the stern of the boat and attached to the exterior of the tubular side and end members of said boat, said spray guard serving to prevent flow of water up over the tubular side and end members of the boat and giving yieldable reinforcement to the boat body.

6. In a pneumatic collapsible boat of the class described, the combination of a tubular flexible fabric boat body with means for inflation to provide buoyancy and a separately inflatable flexible pneumatic floor fitting snugly within the bottom of the boat, and a pneumatic tubular spray guard extending continuously from the bow to adjacent the stern of the boat and attached to the outer side of the body of said boat above the plane of said pneumatic floor.

7. A boat of the class described comprising an inflatable tubular fabric frame constituting side and end portions of the boat, a fabric bottom secured to the lower surfaces of said tubular fabric frame in substantially tangential relation thereto, and a pneumatic floor disposed above said fabric bottom and completely filling the lower portion of the space between the side and end portions of the tubular frame whereby to assist in yieldably maintaining the shape of the boat, said pneumatic floor being free of communication with the tubular frame and comprising spaced apart plural layers of fabric with longitudinally disposed flexible fabric partitions mounted between said layers.

JAMES F. COOPER.
